BURNER ATOMIZER

Filed May 18, 1929

UNITED STATES PATENT OFFICE

JOHN A. PHELAN, OF GALVESTON, TEXAS, ASSIGNOR TO ELBERT B. KNOWLES, OF GALVESTON, TEXAS

BURNER ATOMIZER

Application filed May 18, 1929. Serial No. 364,271.

The present invention relates to improvements in burner atomizers, and has for an object to provide an improved fuel oil or gas burner atomizer of novel and simple construction adapted to effect positive and complete atomization of fuel oil in burners.

Another object of the invention is to provide an improved burner structure in which the flame will be uniformly distributed, practically noiseless and comparatively soft, with the result that the life of furnaces and that of boiler tubes is prolonged.

A further object of the invention is to provide an improved burner in which the parts are standardized, individually replaceable, and easily assembled or readily removed for cleaning when desired, requiring no skilled operator for this purpose.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a longitudinal sectional view taken through an improved burner structure according to the present invention,

Figure 2 is a section taken on the line 2—2 in Figure 1,

Figure 3 is an end view of the supporting casting with parts broken away, and parts shown in section,

Figure 4 is an interior end view of the atomizer box or container,

Figure 5 is a section taken on the line 5—5 in Figure 4 showing the ball member and atomizer disc in operative position,

Figure 6 is a plan view of the atomizer disk, and

Figure 7 is a section taken on the line 7—7 in Figure 6.

Referring more particularly to the drawings, 10 designates the guide pipe and 11 the burner pipe which is located within the guide pipe and is of smaller diameter. The improved atomizer is carried within the pipe 11, upon the outer screw threaded end 50 of which is removably fitted a nut 12 having

a peripheral enlargement sufficient to extend out to and engage the inner wall of the guide pipe 10, which is inwardly of the free end thereof; whereby a support is given to the burner pipe 11 at the end about the atomizer nozzle. The nut 12 is further peculiarly formed in that it carries an inwardly directed flange 13 which is spaced forwardly from the end of the burner pipe 11 when the nut 12 is screwed home on the pipe. In the space between the flange 13 and adjacent end of the pipe 11, are fitted the flange 14 of the atomizer box or container 15, and the peripheral edge of the atomizer disk 16. The box 15 is open at the flanged end 14, and the disk 16 abuts against this open end and closes it save for the burner orifice 17 which is provided in the central portion of the disk 16, which central portion is provided with the external boss or enlargement 18 disposed opposite the central internal cavity 19 with which the tangential grooves 20 communicate. These grooves 20 are made in the inner face of the disk 16, and they communicate at tangents with the semi-spherical cavity 19. As shown in dotted lines in Figure 5, the base walls of the grooves 20 slope or become deeper toward the cavity 19.

The box or container 15 extends inwardly of the pipe 11 and is shown as concentric with the nut 12. The inner end 21 of the container is provided with numerous perforations disposed in one or more circumferential rows or series. In the present instance, an outer series 22 and an inner series 23 are provided, the perforations in the inner row being more numerous and more closely related than the perforations in the outer row 22. The central portion of the end head 21 is blank and formed on its internal face with partially spherical cavity 24. Confined within the container 15 is a ball 25 of larger diameter than the diameter of the cavity 19. This ball seats between the cavity in the disc and the cavity 24 and forms a space 19' establishing communication between the discharge end of the tangential grooves and the burner orifice 17. The oil is forced to pass around the ball in a film and discharges through the tangential

grooves into the space 19'. By reason of the tangential disposition of the grooves 20 the oil is caused to whirl in the space 19'.

At its rear end, the guide pipe 10 is received within a sleeve 26 in which it is held by the set screw 27. The sleeve is part of a casting 28 which, as shown in Figure 3, is of a generally rectangular construction open internally for receiving the head 29, into which the burner pipe 11 is threaded 10 at its inner end. The inner end of the pipe 11 communicates with an annular space 30 within the head, which space extends all about the perforated cylindrical strainer 31. This strainer rests at one end on the closed 15 bottom of the head 29, and at its other end it engages the flanged end 32 of an externally and internally threaded nipple 33. The flanged end 32 engages against the inner portion of the rectangular casing or frame 28, through the upper portion of 20 which the nipple 33 is threaded.

The flange 32 engages in an annular groove 34 upon the open portion of the head 29. The head 29 is provided with the handle or shank 35 for supporting and for removing the head when desired. The closed end of the head 29 is formed externally with a socket 36 to receive the end of the screw 37 having a T-head 38. The nipple 33 is adapted to communicate with a source of oil supply.

In the operation of the device, it will be understood that the container holding the ball 25 is perforated with numerous small holes, the number and size of which depend upon the capacity or output required. These perforations are presented to the fuel in the pipe 11, and the fuel is strained thereby, passing in a film around the ball 25, which is of any appropriate size. The fuel, on going around the ball, is directed to the outer portions of the grooves 20, and in passing down these grooves and into the cavity 19, the fuel acquires a whirling motion. The steel or other ball 25 has innumerable seats, and it forms a seat over chamber and tangents. The grooves 20 may be two or more in number, and the size and shape of the whirling chamber 19 may be changed, if desired.

The atomization is of positive, hollow-cone shape, uniformly thin throughout, similar to air mist in fineness of divided particles, readily admitting a complete mixture with air for combustion. There are no moving parts, no valves to operate, and the device shows high furnace efficiency in operation either with high or low pressure, and 60 has a wide range of fuel temperatures.

The entire atomizer may be removed by unscrewing the nut 12, and the ball 25 may be accessible through the opening apart of the disk 16 and container 15. In a number 65 of cases, the container, ball and disk may be

enclosed in a housing threaded at one end and of such size to fit different sizes of burner pipes now in use. In this simplified method, the burner atomizer may be either installed horizontal, as commonly done, or at right angles or vertical, goose-neck or any other angles, as the case may warrant.

The improved burners are adapted to marine boilers, upright boilers, fire boxes of locomotives, bone char kilns, etc., and they may be used with natural, forced or induced draught with equal effectiveness. The burner may be manufactured at low cost, and replacements will seldom be required other than atomizer plates or disks due to wear of orifice after long service. No ill effects will be noted from heat expansion.

The oil enters through the nipple 33 and passes through the strainer 31, which catches all foreign matter and prevents same from passing to the burner pipe and to the atomization nozzles. By removing the screw 37, the head 29 may be lowered away from the nipple 33 and taken out of the frame 28, whereby easy access is had to the strainer 31 for the purpose of removing, cleaning and replacing the same.

It will be obvious that many changes in the construction, combination and arrangement of parts could be made, which could be used without departing from the spirit of my invention, and I do not mean to limit the invention to such details, except as particularly pointed out in the claims.

Having thus described my invention, what I claim and desire to secure by Letters Patent of the United States is:—

1. A burner atomizer comprising a guide pipe, a burner pipe removably mounted in the guide pipe, an atomizer box projecting into the outer end of the burner pipe and having circular rows of perforations in its bottom and a cavity in the inner face of the bottom within the rows of perforations, an atomizer disc seated against the outer end of said box and having a central burner orifice extending therethrough and having at its inner side a central cavity, a ball mounted in the atomizer box and seated in the cavities of the inner end of the box and the disc and arranged to provide a space in communication with said central orifice, and tangential grooves in said disc establishing communication between said space and said atomizer box and a nut threaded on the end of the burner pipe and having an in-turned flange for clamping the box and the disc to the pipe and having an outstanding spacing portion engaging the inner wall of said guide pipe to space the burner pipe therefrom.

2. A burner atomizer comprising a guide pipe open at one end and having a frame mounted upon its opposite end, a burner pipe removably mounted in spaced relation

and within the guide pipe and having a head upon its inner end removably fitting in said frame, means detachably securing said head in the frame, a nut threaded upon the outer end of the burner pipe and having an outstanding portion adapted to engage the inner wall of the guide pipe to space the burner pipe therefrom and having an in-turned flange at its outer end spaced from the outer end of the burner pipe, an atomizer box fitting in the outer end of the burner pipe and having an out-turned flange seated against the end of the burner pipe, an atomizer disc fitting against the flanged end of the atomizer box to close it and having a central burner orifice extending through the disc, said disc having upon its inner face outwardly extending grooves and a cavity between the inner ends of the grooves and said burner orifice, said grooves extending at a tangent to the cavity, said atomizer box having perforations through its inner end, said flange of the nut adapted to engage the marginal portion of said disc 25 to bind the same against the flange of the atomizer box and hold the latter in the burner pipe, and a ball of greater diameter than said cavity mounted and positioned in the atomizer box to spread oil outwardly toward the grooves.

3. A burner atomizer comprising a guide pipe, a burner pipe removably mounted in the guide pipe, an atomizer device projecting into the outer end of the burner pipe, and a nut threaded on the end of the burner pipe and having an in-turned flange for clamping the atomizer device to the pipe and having an outstanding spacing portion engaging the inner wall of said guide pipe 40 to space the burner pipe therefrom.

JOHN A. PHELAN.
